BOAT

Carl Peters, St. Louis, Mo.

Application February 1, 1947, Serial No. 725,938

4 Claims. (Cl. 114—67)

1

This invention relates generally to boats and more specifically to boats provided with drums rotatably supported at the bottoms of the boats and adapted to facilitate passage of the boats along the water, the predominant object of the invention being to provide a boat of this type which is of such improved construction and arrangement that it is capable of performing its intended function in an improved and highly efficient manner.

Fig. 1 is a plan view of the improved boat of the present invention.

Fig. 2 is a side elevation of the boat illustrated in Fig. 1.

Fig. 3 is an enlarged, fragmentary, vertical section of a portion of the boat illustrated in Figs. 1 and 2 taken on line 3—3 of Fig. 1.

Fig. 4 is a horizontal section taken on line 4—4 of Fig. 3.

Fig. 5 is a fragmentary section taken on line 5—5 of Fig. 4 and looking in the direction indicated by the arrows.

Fig. 6 is an enlarged, fragmentary, vertical section taken on line 6—6 of Fig. 1.

Fig. 7 is an enlarged, fragmentary, vertical section taken on line 7—7 of Fig. 3.

Fig. 8 is an enlarged, fragmentary, vertical section taken on line 8—8 of Fig. 2.

In the drawings, wherein is shown for purposes of illustration, merely, one embodiment of the invention, A designates the improved boat generally. The boat A comprises a hull structure 1 which is provided with a forward deck 2, the forward portion of the boat being preferably shaped as shown in Figs. 1 and 2. The hull 1 of the boat A is provided with a plurality of cavities 3, 4, 5a and 5b which extend transversely of said hull, said cavities being spaced longitudinally of the boat hull, as is shown to good advantage in Fig. 2. The cavities 3 and 4 are formed by curved portions 6 and 7 of the bottom wall of the boat hull and by removable, curved closure members 8 which extend in the case of each of the cavities 3 and 4 from the upper end of the curved wall portion 6 to the upper end of the curved wall portion 7.

By referring to Fig. 3 it will be noted that an arcuate element 9 is associated with the curved wall portion 6 of the cavity 3 at the top thereof, said arcuate element 9 being extended transversely of the boat hull 1 and being welded, or otherwise secured to the upper portion of said curved wall portion 6 of the boat hull and to opposite side portions 1' of the boat hull. Also, as is shown in Figs. 3 and 4, the arcuate element

2

9 has welded or otherwise secured thereto a pair of similar arcuate elements 10 whose outer ends may, if desired, be welded, or otherwise secured, to the opposite side portions 1' of the boat hull, and whose inner ends are spaced apart, as is shown in Fig. 4. The removable closure member 8, shown in Fig. 3, is provided at one of its ends with an offset portion 8a which overlaps portions of the arcuate elements 9 and 10, and at its 10 opposite end said removable closure member 8 is provided with a similar offset portion 8b which overlaps a portion of a transversely extended brace 11 which is welded, or otherwise secured to the curved portion 7 of the boat hull. The offset portions 8a and 8b are secured, respectively, by suitable fastening devices to the combined arcuate elements 9—10 and to the brace 11. Also, the removable closure member is provided with elongated vent openings 12 through which air may pass from the interior of the cavity 3, said openings being formed by suitably slitting and offsetting portions of the removable closure member 8 as is shown in Fig. 3.

The cavity 4 of the boat A is constructed in accordance with the details of construction of the cavity 3 as described above; that is to say said cavity 4 is provided with an arcuate element 9 which is extended transversely of the boat and which is welded, or otherwise secured, to the top part of the curved wall portion 6 of said cavity 4 and to opposed side wall portions of the boat hull. Likewise, the arcuate element 9 has welded, or otherwise secured thereto, arcuate elongated elements 10 which extend transversely of the boat hull. Additionally, the curved, removable closure member 8 of the cavity 4 is provided with offset portions at its opposite ends which overlap and are respectively secured to the arcuate elements 9 and 10 and to a transversely extended brace 11, said closure member being provided, also, with elongated vent openings 12.

The cavity arrangement at the rear of the boat A differs slightly in arrangement from the construction of the cavities 3 and 4 as previously described herein. In other words, the cavities 3 and 4 extend transversely of the boat hull 1 continuously from side to side thereof, while at the rear of the boat a pair of transversely aligned cavities 5a and 5b are provided which are spaced apart at their inner ends (Fig. 1). The cavities 5a and 5b are constructed somewhat in accordance with the constructions of the cavities 3 and 4 in that each of said cavities 5a and 5b includes a curved wall portion 13 which has welded, or

otherwise secured, to its upper end an elongated arcuate element 14, which resembles the arcuate element 9 of the cavities 3 and 4, these elongated, arcuate elements 14 being welded, or otherwise secured, at their opposite ends to opposed side walls of the cavities 5a and 5b. Also, the elongated, arcuate elements 14 each has welded, or otherwise secured thereto, arcuate elements 15 which resemble the arcuate elements 10 of the cavities 3 and 4. The rear portions of the 10 cavities 5a and 5b are produced by hoods 16 which are shaped as shown in Figs. 1 and 2, said hoods being removably secured in place by suitable fastening devices, and said hoods being provided with vent openings 16' formed there-through.

A horizontal wall 19 (Fig. 6) is disposed in the space between the inner walls of the cavities 5a and 5b, said horizontal wall being welded, or otherwise secured in place. The horizontal wall 19 has secured thereto, by welding or otherwise an upwardly and rearwardly inclined wall 20 which is secured at its opposite edges to the inner walls of the cavities 5a and 5b, and this inclined wall has fixed thereto at its top a plate 21. The inclined wall portion 20 is adapted to serve as a support for an outboard motor, as is illustrated by broken lines in Fig. 6 wherein the outboard motor is designated by the reference character M, the clamping means M' of the outboard motor M being adapted to clampingly engage the upper portion of the inclined wall 20 and the plate 21.

At opposite sides of the cavity 3 and of the cavity 4 bearing structures 22 are provided which support for rotation within said cavities hollow, cylindrical drums, the drum disposed within the cavity 3 being designated by the reference character 23, while the drum disposed within the cavity 4 is designated by the reference character 24.

The drums 23 and 24 are air-tight and watertight and are elongated, said drums being buoyant and being extended transversely of the cavities 3 and 4. The bearing structures 22 comprise each a pair of horizontally extended, vertically spaced angle members 25 which are welded, or otherwise secured, to an adjacent side wall portion of the boat hull 1, as is shown to good advantage in Fig. 7. Arranged adjacent to the pair of spaced members 25 of each bearing structure 22 is an arm 26, the related arms 26 of each cavity 3 and 4 being joined at corresponding ends thereof by a tie rod 27 (Fig. 4). The opposite end portions of the arms 26 extend through aligned apertures 28 formed through the arcuate elements 9 and 10, as is shown in Figs. 3 and 4, and secured to the arcuate elements 10 are bearings 29 by which the arms 26 are supported for pivotal movement. The bearings 29 comprise each a closed housing 30 which is provided with a flange portion 30' which is secured to the arcuate elements 10, the end portions of the arms 26 being extended into the interiors of the bearing housings 30 and being pivotally connected thereto by pivot pins 31, the openings in the housings 30 which receive the pivot pins being sealed by plugs 31' (see upper portion of Fig. 4).

In order to prevent water from entering the interior of the bearing housings 30 each arm 26 has associated therewith a boot 32 which is formed of suitable flexible material. One end of each boot 32 is secured in a water-tight manner to the arm 26 with which it is associated and its opposite end is secured in a water-tight manner

5 to the related arcuate element 9 so that the latter end of said boot surrounds the openings 28 formed through the arcuate elements 9 and 10 through which the arm extends. The boots 32, because of their flexible character are capable of moving with the arms 26 with which they are related and they serve to effectively prevent water from passing through the openings 28 into the interior of the bearing housings 30.

6 Each of the drums 23 and 24 has secured to its opposite end walls flange structures 33 which support outwardly extended trunnions 34. The outer end portions of these trunnions project into bearing members 35 that are provided with flanges 35' which are secured to the related arms 26 by suitable fastening devices, and as a result of such arrangement the drums 23 and 24 are supported by the related arms 26 for free rotation about their axes. The related pair of members 25 of each bearing structure 22 has welded, or otherwise secured thereto, a substantially U-shaped member 36, and interposed between the top, horizontal leg of each U-shaped member 36 and the related arm 26 is a pair of coil springs 38, the upper end portions of said coil springs being seated in spring seats 38a which are associated with said top, horizontal leg of the U-shaped member 36 while the lower end portions of said coil springs are seated in corresponding spring seats 38b associated with the related arm 26 (see Fig. 7). Each U-shaped member is provided with a rod 37 which extends from top to bottom of said U-shaped member and limits inward movement of the related arm 26. Because 30 of the arrangement described above the drums 23 and 24 are supported for vertical movement, the arms 26 swinging from their pivots 31 during such movement of said drums, and the coil springs resisting and limiting upward movement of said 40 drums in an obvious manner.

Disposed within the cavities 5a and 5b at the rear of the boat A is a pair of hollow cylindrical drums 39 and 40. The drums 39 and 40 are constructed in accordance with the construction of 45 the drums 23 and 24 as previously described herein with the exception that the drums 39 and 40 are of substantially less length than are the drums 23 and 24. Additionally, the drums 39 and 40 are supported at their opposite ends by 50 bearing structures constructed in accordance with the bearing structures 22 previously described herein. Thus, the drums 39 and 40 are supported by their associated bearing structures for free rotation about their axes, and, also, said 55 drums 39 and 40 are capable of moving vertically, the pivotally supported arms 26 by which they are supported moving pivotally during vertical movement of said drums, and the coil springs 38 resisting upward movement of the arms 26 and of 60 the drums 39 and 40 supported thereby.

In order to brace the boat hull a plurality of 65 bracing elements 41 are extended longitudinally of said boat hull at the transverse center thereof, as is shown to good advantage in Figs. 1 and 2. Preferably the bracing elements are T-shaped in cross-section and they are welded, or otherwise secured, to inner faces of portions of the boat hull. Also, similar curved bracing elements 41' are secured to the closure members 8 at the 70 transverse center thereof and these bracing elements 41' are aligned longitudinally of the boat with the bracing elements 41.

In the use of the improved boat of the present invention the forward curved portion 1a of the bottom of the boat and the curved portions

7 of the bottom of the boat serve to properly support the boat in the water and guide the water relative to the drums 23, 24, 39, and 40. These curved portions of the boat bottom are of extreme importance because in their absence the drums would drag in the water to such extent, during forward movement of the boat, as to seriously interfere with rapid movement of the boat through the water. However, with the curved portions present the water is directed thereby to the bottom portions of the drums whereby the boat is caused to travel rapidly at the surface of the water. Additionally, side wall portions of the hull of the boat are bowed outwardly, as indicated at 43 in Figs. 1, 2, and 8, so as to give stability to the boat in the water and render tipping of the boat less likely.

The vent openings 12 of the closure members 8 of the cavities 3 and 4, and the vent openings 16 of the hoods 16 of the cavities 5a and 5b serve an important function in that said openings permit air to pass therethrough into and from said cavities. In other words, when one of the cavities moves above the surface of the water and then dives downwardly into the water no air is trapped within the cavity which would interfere with downward movement of the boat in the water as the air within the cavity is permitted to pass from the cavity through the vent openings. In like manner suction created within a cavity 3, 4, 5a or 5b by upward movement of the boat causes air to be sucked into the cavity through the vent openings. Another important feature of the present invention arises from the fact that the drums 23, 24, 39 and 40 are capable of moving upwardly with the pivoted arms by which they are supported and against the forces exerted by the coil springs 38. Thus, shocks caused by the drums striking the surface of the water, waves, or submerged obstructions are materially lessened whereby the operating efficiency of the boat is increased and the drums are protected from injury.

I claim:

1. A boat comprising a hull provided with a cavity formed therein which is extended transversely of said hull from side to side thereof and is open at the bottom thereof, a hollow cylindrical drum disposed in said cavity and extended from side to side of said hull with the lower portion of said drum extending below the bottom of said hull, means for supporting said drum for free rotation about its axis and for vertical movement within said cavity, said drum supporting means including pivotally supported arms disposed at opposite ends of said drum, bearing elements on said arms, trunnions for rotatably connecting said drum to said bearing elements, vertically spaced elongated elements at opposite ends of said drum which are arranged substantially parallel with respect to said pivotally supported arms and between which said arms are disposed, and spring means engaging said pivotally supported arms and certain of said vertically spaced elements for resisting upward movement of said arms, and a curved hull portion leading rearwardly of said hull to said cavity for directing water to the lower portion of said drum.

2. A boat comprising a hull provided with a cavity formed therein which is extended transversely of said hull from side to side thereof and is open at the bottom thereof, a hollow cylindrical drum disposed in said cavity and extended from side to side of said hull with the lower portion of said drum extending below the bottom of said

5 hull, means for supporting said drum for free rotation about its axis and for vertical movement within said cavity, said drum supporting means including pivotally supported arms disposed at opposite ends of said drum, means for excluding water from the pivots of said pivotally supported arms, bearing elements on said arms, trunnions for rotatably connecting said drum to said bearing elements, vertically spaced elongated elements at opposite ends of said drum which are arranged substantially parallel with respect to said pivotally supported arms and between which said arms are disposed, and spring means engaging said pivotally supported arms and certain of said vertically spaced elements for resisting upward movement of said arms, and a curved hull portion leading rearwardly of said hull to said cavity for directing water to the lower portion of said drum.

20 3. A boat comprising a hull provided with a cavity formed therein which extends transversely of said hull from side to side thereof and which is open at the bottom of said hull, a removable closure member forming a wall portion of said cavity, a hollow cylindrical drum disposed in said cavity and extended from side to side of said hull with the lower portion of said drum extending below the bottom of said hull, means for supporting said drum for rotation about its axis, and a curved hull portion leading rearwardly of said hull to said cavity for directing water to the lower portion of said drum.

25 4. A boat comprising a hull provided with a cavity formed therein which is open at the bottom of said hull and which extends transversely of said hull from side to side thereof, a hollow cylindrical drum disposed in said cavity and extended from side to side of said hull with the lower portion of said drum extending below the bottom of said hull, means for supporting said drum for free rotation about its axis, a pair of 30 cavities adjacent to the rear end of said hull which are aligned transversely of said hull and are spaced apart at their inner ends, a hull portion located between said spaced pair of cavities and adapted to support a motor and rudder structure, hollow cylindrical drums disposed within said pair of cavities with the lower portions of said drums extending below the bottom of said hull, means for supporting the last-mentioned drums for free rotation about their axes, and curved hull portions leading rearwardly of said hull to the first-mentioned cavity and to each of said pair of cavities for directing water to the lower portions of the drums disposed within said cavities.

CARL PETERS.
